(57) **CLAIM**

I claim the ornamental design for an air removal device, as shown and described.

DESCRIPTION

FIG. 1 is a top front perspective view of the claimed design; FIG. 2 is a right side elevation view thereof; FIG. 3 is a left side elevation view thereof; FIG. 4 is a front elevation view thereof; FIG. 5 is a rear elevation view thereof; FIG. 6 is a top plan view thereof; and, FIG. 7 is a bottom plan view thereof. The features shown in broken lines depict environmental structure only and form no part of the claimed design.
